UNITED STATES PATENT OFFICE.

LOUIS A. KNOOPP, OF ST. LOUIS, MISSOURI, ASSIGNOR TO BRODERICK & BASCOM ROPE CO., OF ST. LOUIS, MISSOURI, A CORPORATION OF MISSOURI.

LOADING CHUTE.

Application filed December 19, 1923. Serial No. 681,530.

To all whom it may concern:

Be it known that I, LOUIS A. KNOOPP, a citizen of the United States, residing at St. Louis, Missouri, have invented a new and 5 useful Loading Chute, of which the following is a specification.

This invention relates to loading chutes.

An object of the invention is to provide a loading chute with a pivoted lip at its discharge end capable of being raised to permit a bucket or other receptacle to be moved quickly to receiving position below the lip, in combination with a gate above the lip, and means for operating the gate and the 15 lip in an order in which the gate nearly closes the chute before the lip begins to rise.

Another object of the invention is to provide a chute with a gate movable to open and to closed positions, and a compound 20 system of rollers for holding the gate in proper alignment during operation.

Another object of the invention is to provide a chute embodying all of the useful and advantageous subject matter herein 25 disclosed.

In the drawings, Fig. 1 is a side elevation of the invention.

Fig. 2 is a view showing the roller and track devices for guiding the gate.

Fig. 3 is a plan view further showing the 30 roller and track structure.

Fig. 4 is a view looking upwardly toward the lower end of the chute.

Fig. 5 is a view showing the counter- 35 weight device in connection with the levers that operate the chute door and lip.

Fig. 6 is a detail view showing the connection between the counterweight devices and the levers.

Fig. 7 is a view showing the pivotal 40 connection between the lip and the chute proper.

The chute in connection with which the present invention is shown comprises an 45 inclined bottom wall 1 and vertical side walls 2. Near the lower or discharge end of the chute the bottom wall 1 and the side walls 2 are divided throughout the width of the bottom wall and the height of the side walls forming a slot 3 through which the 50 gate 4 is movable to open and to closed positions. The adjacent portions of each side

wall are connected by brackets 5 thereby securing the two separated portions of the 55 chute in rigid connection.

The side edges of the gate 4 extend outwardly beyond the outer sides of the side walls 2. Each of the side edges has attached thereto a pair of roller supports 6 and each roller support is equipped with a pair of 60 rollers 7 operating on axes at right angles to each other and against the flanges of a track member 8 attached to the side walls 2 and extending downwardly a considerable 65 distance below the chute. These parts are arranged in such relationship that one flange of each track member 8 is adjacent to and parallel with the extended side edge of the gate 4, while the other flange of each track member is secured flat against the side 70 wall 2 of the chute; two of the rollers 7 at each side of the chute operate against the flange of the track 8 that is parallel with and adjacent to the gate 4, while the other two rollers at each side of the chute operate 75 against the flanges of the tracks 8 that are against the side walls 2. This provides a compound roller arrangement which prevents the gate from becoming jammed or biased and renders operation of the gate 80 easy and positive.

The lip that is pivoted to the lower end of the chute comprises a bottom wall 9 and side walls 10. The bottom wall 9 of the lip extends under the lower end of the bottom wall 1 of the chute, while the side walls 10 of the lip embrace the side walls 2 of the chute between them. The chute is pivotally supported on pivots 11 extending through the side walls 2 of the chute and through the 85 side walls 10 of the lip and through a strengthening strap 12 attached to the side walls 2 above the lip and extending downwardly at the outer sides of the lip side walls 10, so that the side walls of the lip 90 operate between the side walls 2 of the chute and the straps 12.

A rock shaft 13 is mounted in a support which may be in the form shown or of other construction, as desired. The support 100 shown comprises a pair of bars 14 having their upper ends attached to the pivots 11 and their lower ends supporting the shaft 13. Angle irons 15 are attached at their up-

per ends to the track members 8 and have their lower ends provided with holes through which the shaft 13 extends for rocking movements. The upper ends of the

5 angle irons 15 are rigidly connected by a cross member 16 so that the support for the shaft 13 is made rigid.

The shaft 13 supports a bell crank lever of which the arm 17 is connected by links 18 with a bracket 19 attached to the lower edge of the gate 4. The other arm 20 of the bell crank lever referred to has pin in slot connection 21 with the lower end of a link 22, the upper end of which is pivoted 10 to a bracket 23 attached to the bottom wall 9 of the lip between the pivot 11 and the upper end of the lip. The shaft 13 is provided with operating means which, as shown, comprises a lever 24.

15 The connections between the bell crank lever 17—20 and the gate 4 and the lip are such that when the lever 24 is operated the gate 4 will be raised nearly to closed position, that is nearly to the height of the side walls of the chute before the lip begins to move. The result is that the movement of the material along the chute is stopped by the gate before the lip begins to move, thus affording time for all of the material below 20 the gate to be discharged from the lip before the lip is operated. When the lever 24 is operated the parts are moved to the position shown by dotted lines (Fig. 1), thereby raising the lower end of the lip to a sufficient height to permit a tramway bucket or other receptacle to be moved quickly to receiving position close to the discharge end of the chute. When the parts are operated to lower the lip and open the gate, the lip 25 is lowered rapidly placing the lower discharge end thereof directly above the bucket or receptacle before the gate opens. This insures that the material will be discharged into the bucket or receptacle.

30 45 The connection between the arm 20 of the bell crank lever and link 22 supports a counterbalance weight 25 which assists in the operation.

50 From the foregoing it will be seen that my invention obtains all of its intended objects and purposes in a highly efficient manner. The gate is held by the system of compound rollers so that it is impossible for it to become jammed or biased, and the operation of the parts is timed in such relationship that best results are obtained.

55 I am aware that the construction and arrangement may be varied considerably without departure from the nature and principle 60 of the invention. I do not restrict myself unessentially, but what I claim and desire to secure by Letters Patent is:—

65 1. In a loading chute, a gate for closing the chute above the discharge end, a lip pivotally supported at the discharge end of the

chute, and mechanism for operating the gate and the lip in a time order in which the gate is moved nearly to closed position before the lip is moved.

2. In a loading chute, a gate for closing 70 the chute above the discharge end, a lip pivotally supported at the discharge end of the chute, and mechanism for operating the gate and the lip in a time order in which the gate is moved nearly to closed position 75 before the lip is moved and in which the lip is returned to delivery position before the gate is opened.

3. In a loading chute, a gate for closing 80 the chute above the discharge end, a lip pivotally supported at the discharge end of the chute, mechanism for operating the gate and the lip in a time order in which the gate is moved nearly to closed position before the lip is moved, and a counterweight device 85 co-operating with said mechanism and facilitating operation thereof.

4. In a loading chute, a gate for closing the chute, a right angled track member at each side of the chute, a number of rollers 90 supported by the gate on axes at right angles to each other and certain of said rollers operating against one angle of the adjacent track member and the remaining rollers operating against the other angle of the track 95 member, and means for operating the gate.

5. In a loading chute, a gate for closing the chute, a right angle track member at each side of the chute, a number of rollers supported by the gate on axes at right angles to each other and certain of said rollers operating against one angle of the adjacent track member and the remaining rollers operating against the other angle of the track member, a rock shaft, a lever attached to 100 the rock shaft beyond one side of the chute, a lever attached to the rock shaft in alignment with the gate, and a connection between said second lever and the gate.

6. A loading chute comprising a gate for 110 opening and closing the chute, a lip pivoted to the lower discharge end of the chute, operating mechanism movable to and from a starting position, means for operating the gate to closed position during entire movement of the operating mechanism from starting position, and means for raising the lower end of the lip during the final movement of the operating mechanism from starting position.

7. A loading chute comprising a gate for opening and closing the chute, a lip pivoted to the lower discharge end of the chute, operating mechanism movable to and from a starting position, means for operating the 125 gate to closed position during entire movement of the operating mechanism from starting position, and means for raising the lower end of the lip during the final movement of the operating mechanism from 130 starting position.

starting position and lowering the lip during initial movement of the operating mechanism toward starting position.

8. A chute comprising side and bottom walls, a gate for closing the chute, mechanism for operating the gate, and the herein described system of compound rollers for guiding the gate.

9. A loading chute comprising side and bottom walls, right angled track members attached to said side walls, a gate for opening and closing the chute, series of rollers supported by the gate and operating against both angles of said track members, and mechanism for operating the gate.

10. A loading chute comprising side and bottom walls, right angled track members attached to said side walls, a gate for opening and closing the chute, series of rollers supported by the gate and operating against both angles of said track members, a rock shaft, a lever attached to the rock shaft beyond the side of the chute, and a connection between said shaft and the gate beneath the chute.

11. A loading chute comprising side and bottom walls composed of spaced sections, a gate operable in the space between said sections to open and to close the chute, rigid connections between the sections of the side walls, right angled track members attached to the side walls, and the herein described system of compound rollers supported by the gate and operating against both angles of the respective track members.

12. A loading chute comprising side and bottom walls composed of spaced sections, a gate operable in the space between said sections to open and to close the chute, rigid connections between the sections of the side walls, right angled track members attached to the side walls, the herein described system of compound rollers supported by the gate and operating against both angles of the respective track members, in combination with a lip pivoted to the lower end of the chute, and mechanism operable to move

the gate toward closed position during the entire movement of said mechanism from a starting position and to raise the lip during final movement from starting position.

13. A loading chute comprising side and bottom walls composed of spaced sections, a gate operable in the space between said sections to open and to close the chute, rigid connections between the sections of the side walls, right angled track members attached to the side walls, the herein described system of compound rollers supported by the gate and operating against both angles of the respective track members, in combination with a lip pivoted to the lower end of the chute, and mechanism operable to move the gate toward closed position during the entire movement of said mechanism from a starting position and to raise the lip during final movement from starting position, and to permit the lip to lower during initial movement toward starting position and to open the gate during entire movement toward starting position.

14. A loading chute comprising side and bottom walls composed of spaced sections, a gate operable in the space between said sections to open and to close the chute, rigid connections between the sections of the side walls, right angled track members attached to the side walls, the herein described system of compound rollers supported by the gate and operating against both angles of the respective track members, in combination with a lip pivoted to the lower end of the chute, mechanism operable to move the gate toward closed position during the entire movement of said mechanism from a starting position and to raise the lip during final movement from starting position, and to permit the lip to lower during initial movement toward starting position and to open the gate during entire movement toward starting position, and a mechanical element facilitating the operation of said mechanism.

LOUIS A. KNOPP.
